HOOK

La Verne E. Clayton, Rockford, Ill., and Martin R. Lambertz, New Hamburg, Ontario, Canada, assignors to Amerock Corporation, Rockford, Ill.

Filed June 24, 1970, Ser. No. 33,634

Term of patent 14 years

Int. Cl. D8—03

U.S. Cl. D8—254

FIG. 1 is a side view of a hook incorporating our new design.

FIG. 2 is a front view of the hook.

FIG. 3 is a rear view of the hook.

FIG. 4 is a top plan view of the hook.

FIG. 5 is a sectional view taken along the line 5—5 in FIG. 1.

FIG. 6 is an enlarged sectional view taken along the line 6—6 in FIG. 1.

FIG. 7 is an enlarged sectional view taken along the line 7—7 in FIG. 1.

FIG. 8 is an enlarged sectional view taken along the line 8—8 in FIG. 1.

FIG. 9 is an enlarged sectional view taken along the line 9—9 in FIG. 1.

FIG. 10 is an enlarged sectional view taken along the line 10—10 in FIG. 1.

FIG. 11 is an enlarged sectional view taken along the line 11—11 in FIG. 1.

The portions shown in broken lines are for purposes of illustration only.

We claim:

The ornamental design for a hook, as shown and described.
